UNITED STATES PATENT OFFICE.

THOMAS W. BAKER, OF SPOKANE, WASHINGTON.

REINFORCED HOLLOW BRICK WALL.

1,318,828.

Specification of Letters Patent.

Patented Oct. 14, 1919.

Application filed October 26, 1917. Serial No. 198,638.

To all whom it may concern:

Be it known that I, THOMAS W. BAKER, a citizen of the United States, residing at Spokane, in the county of Spokane and State of Washington, have invented certain new and useful Improvements in Reinforced Hollow Brick Walls; and I do hereby declare the following to be a full, clear, and exact description of the invention, such as will enable others skilled in the art to which it appertains to make and use the same.

This invention relates to a reinforced hollow brick wall.

The object of the present invention is to improve the construction of walls and to provide a simple, practical and efficient reinforced hollow brick wall adapted to lighten the construction and enable the wall to be constructed of less material and at the same time exclude moisture, cold and heat.

With these and other objects in view, the invention consists in the construction and novel combination of parts hereinafter fully described, illustrated in the accompanying drawing and pointed out in the claim hereinafter appended; it being understood that various changes in the form, proportion, size and minor details of construction, within the scope of the claim, may be resorted to without departing from the spirit or sacrificing any of the advantages of the invention.

In the drawing:

Figure 1 is a perspective view of a portion of a hollow brick reinforced wall constructed in accordance with this invention.

Fig. 2 is a transverse sectional view of the same.

Fig. 3 is a detail view of one of the half or corner bricks shown in Fig. 1.

Like numerals of reference designate corresponding parts in all the figures of the drawing.

In the accompanying drawing, in which is illustrated the preferred embodiment of the invention, the reinforced hollow brick wall, which may be constructed of two, three or four inch brick, or in fact brick of any desired size, is composed of a plurality of wall sections or members, inner, intermediate and outer sections 1, 2 and 3 being shown in Fig. 1, but the number of wall sections or members may of course be varied to provide a wall of the desired dimensions and strength to suit requirements. The wall

sections or members consist of bricks 4 laid in courses and provided with openings 5 preferably located at the center and ends as shown and, when the wall sections or members are made up of a single tier or brick or a thickness equal to the width of a brick, half bricks 6 having central openings 7 may be employed but the size of the bricks and the thickness of the wall sections or members may be of course varied, as will be readily understood.

The brick are laid in layers or courses in the ordinary manner and the wall sections or members are tied together at every five or six or seven courses by tie bricks 8 of twelve inches in length or of sufficient length to span the spaces 9 between the parallel sections or wall members 1, 2 and 3, and the said tie bricks 8, which may be of any desired length, are provided at their end portions with openings 10 adapted to register with openings of the bricks 4 or 6, as clearly illustrated in Fig. 2 of the drawing. The transversely disposed tie bricks may be arranged one upon the other as shown and they are located at regular intervals and their openings, which are filled with mortar keys 11, are arranged to receive dowel pins 12 constructed of steel or other suitable material and which pass through the openings of the transversely disposed tie bricks and project upwardly and downwardly beyond the same so as to extend into the openings of the adjacent bricks 4 or 6 to provide a mechanical bond between the vertical wall sections or members. The projecting terminals of the dowel pins engage the mortar in the openings of the bricks of the wall sections or members, the laying of the bricks in the usual manner filling the upper portions and lower portions of the bricks of the wall sections or members, as shown. By this construction, the dowel pins will be embedded in the mortar and will firmly tie the wall sections together. When the transversely disposed tie bricks 8 are arranged at their adjacent ends upon each other as shown in Fig. 2, an elongated dowel pin 13 of sufficient length to extend through both of the tie bricks and project beyond the same to engage the adjacent bricks of the wall sections may be used. The hollow wall, by reason of the intervening spaces between the wall sections or members, is adapted to exclude heat, cold and moisture and by reason of the said spaces less ma-

terial will be employed in the construction of the wall and a lighter construction without any diminution in the strength of the wall will be provided. Also the dowel pins 5 provide a reinforced wall and a mechanical binding between the wall sections or members. The number and size of the openings of the bricks may be varied and the structure is applicable to walls of various 10 thicknesses.

What is claimed is:

A wall comprising inner, outer and intermediate spaced parallel sections, each section including superposed layers of blocks; 15 pairs of transverse stretcher blocks having their inner end portions overlapping vertically and mounted in the intermediate sec-

tion and having their outer end portions mounted in the outer sections, the end portions of said stretcher blocks and the adjacent blocks of said sections being provided with alining openings; mortar keys arranged in said openings; and vertical dowel pins embedded in said mortar keys and connecting the end portions of the stretcher 20 blocks and the upper and lower adjacent blocks of said sections.

In testimony whereof I affix my signature in presence of two witnesses.

THOMAS W. BAKER.
